Goding Wallway
Setters Patent

Marked up referred to in this Settler Patent and making part of the same
containing a description in the word of the said Goding Wallway,
tunels of his improvement in Horses' Chaps.

The Chap is composed of wood and leather of a diamond or other
form, and may consist of 1, 2, 3 or 4 sides around a central with the
hemp after mentioned and described ingredients for the purpose of grind-
ing, honing, polishing or smoothing, and cutting a fine edge to razors or
other instruments requiring the same. The composition for coating or
covering the leather after being glued to the Stock is, made and applied
as follows viz. You take 3 parts of manacle or mullen leather & parts
taken one part to be milled together, and run into a cake with
which the several different sides of the Chap are to be rubbed until
the leather is, well saturated with it. There for and upon this
coarse side intended for ^{grinding} denominated No. 1. Emery of a
suitable coarse grain is applied by dusting it through Stock mus-
lin, and rubbed or worked into the composition or coating upon the leather
by means of a glass roller until it becomes smooth, repeating the applica-
tion of the latter composition, dusting with emery and rolling or
rubbing it in until the leather or surface of the Chap is completely
coated, for No. 2. or the side designed for honing. A small portion
of Bosphian blue finely pulverized is to be added after a coat of emery
of coarse grain, the first, each to be dusted on separately and alternately
in like manner, through muslin of a corresponding fineness rolled
and worked in with composition as before. No. 3. or third side for
cutting a sharp edge smoothing &c. A light coat of the flour of
cass is to be dusted as before through muslin of a still finer quality
preceded by an equal quantity or coat of flour of emery repeated and
worked in alternately with the composition same as before.
The last side No. 4. is to be lightly rubbed with the cake and
then polished down to the most perfect smoothness with the glass

soller, after which a small portion of prussian vermilion is applied, dusting it over with a fine abr. or silk puff until the whole surface is evenly covered. What the said Gooding Holloway considers as his new process and for which he takes; and expects a patent is embodied in the following particular. First in preparing a composition with additional ingredients of resin & turpentine or tallow which produces a strong adhesive quality, and of such permanency that it will not be easily peal to change, decay or pull off from the leather, but on the contrary gives firmness by using. thereby retaining and preserving entire upon the surface of the face of the shape its superior properties for a great length of time, increasing its utility and value beyond any other strap hitherto manufactured, or known.

Secondly by the additional use of prussian blue the pores of the second side are more perfectly filled up rendering it solid and permanent and of the nature of a sharp [unintelligible] Thirdly the application and use of the flour of emery which besides, its fine polishing or smoothing property holds permanency an exceedingly sharp and fine grit of a soft nature than Emery, impacting and preserving an indispensible qualification to the third side of the strap. And lastly the prussian vermilion which operates in giving the finishing stroke of finest possible edge, and also prevents the surface of the last and delicate side of the strap from abrading all which I claim as my improvement.
